UNITED STATES PATENT OFFICE.

GEORGE M. MOISSON, OF GREENVILLE, SOUTH CAROLINA.

DESIGN FOR A CIRCUS TOY WAGON.

Application filed May 3, 1928. Serial No. 26,554. Term of patent 3½ years.

To all whom it may concern:

Be it known that I, GEORGE M. MOISSON, a citizen of the United States of America, and a resident of Greenville, in the county of Greenville and State of South Carolina, have invented a new, original, and ornamental Design for a Circus Toy Wagon, of which the following is a specification, reference be-

ing had to the accompanying drawing, forming part thereof.

The figure is a perspective view of a circus toy wagon showing my new design.

I claim:

The ornamental design for a circus toy wagon, as shown.

GEORGE M. MOISSON.
